US0D1079817S

(12) United States Design Patent (10) Patent No.: US D1,079,817 S
(45) Date of Patent: * Jun. 17, 2025

(54) GAMING MACHINE ISLAND

(71) Applicant: Aristocrat Technologies Australia Pty Limited, North Ryde (AU)

(72) Inventors: Scott Olive, Brookvale (AU); John Curtis, Biddaddaba (AU)

(73) Assignee: Aristocrat Technologies Australia Pty Limited, North Ryde (AU)

() Term: 15 Years

(21) Appl. No.: 29/965,021

(22) Filed: Sep. 25, 2024

Related U.S. Application Data

(60) Continuation of application No. 29/957,337, filed on Aug. 13, 2024, which is a continuation of application No. 29/896,636, filed on Jul. 6, 2023, which is a continuation of application No. 29/858,197, filed on Oct. 28, 2022, now Pat. No. Des. 995,643, which is a continuation of application No. 29/810,260, filed on Oct. 4, 2021, now Pat. No. Des. 971,337, which is a continuation of application No. 29/771,639, filed on (Continued)

(57) CLAIM

The ornamental design for a gaming machine island, as shown and described.

DESCRIPTION

FIG. 1 is a front perspective view of a gaming machine island showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the gaming machine island that form no part of the claimed design.

1 Claim, 7 Drawing Sheets

Related U.S. Application Data

Feb. 24, 2021, now Pat. No. Des. 934,346, which is a division of application No. 29/708,289, filed on Oct. 4, 2019, now Pat. No. Des. 914,807.
